US00D771380S

(12) **United States Design Patent** (10) **Patent No.:** **US D771,380 S**
(45) **Date of Patent:** **** Nov. 15, 2016**

(54) **AMMUNITION CRATE**

(71) Applicant: **Steven W. Minneman**, Clayton, OH (US)

(72) Inventor: **Steven W. Minneman**, Clayton, OH (US)

(73) Assignee: **MTM Molded Products Company**, Dayton, OH (US)

(**) Term: **15 Years**

(21) Appl. No.: **29/528,086**

(22) Filed: **May 26, 2015**

(51) **LOC (10) Cl.** 03-01

(52) **U.S. Cl.**

USPC **D3/262**

(58) **Field of Classification Search**

USPC D3/201, 203.6, 262, 273, 276, 281, 282,
D3/294

CPC .. A45C 13/1084; A45C 5/00; A45C 13/008;
E05B 65/5276
